WORK HOLDER

Warren H. Farr, Grosse Pointe Farms, and Eugene P. Hawthorne, Detroit, Mich., assignors to Budd Wheel Company, Philadelphia, Pa., a corporation of Pennsylvania

Application June 1, 1943, Serial No. 489,284

7 Claims. (Cl. 294—87)

This invention relates to work holders of the type in which a plurality of workpieces are conveyed from one operating unit to another and subjected to the successive operations thereof while supported on the work holder.

In the operation of such devices it is sometimes found that different spacing between the work-piece centers is required at the different units. For example, the center spacing for a heating furnace may be substantially less than that for a quenching bath, a cleaning machine, or the like. An object of this invention is to provide a work holder constructed and arranged to permit variable center spacing between a plurality of work supports to meet the different requirements of successive operating units.

A further object is to provide a work holder in which either short or long center spacing can be instantly obtained by a single adjustment accomplished during travel of the work holder between units.

These and other objects which will be apparent are accomplished by the present invention, one embodiment of which is shown in the accompanying drawings in which:

Fig. 1 is a view in elevation showing a pair of work holders, constructed in accordance with one embodiment of this invention, at different operating stations for subjecting a plurality of workpieces suspended thereon to successive operations;

Fig. 2 is a sectional view through one of the work holders shown in Fig. 1, illustrating the work supports as located in their relatively closely spaced position;

Fig. 3 is a sectional view on the line 3—3 of Fig. 2;

Fig. 4 is a similar view on a somewhat enlarged scale showing the adjusting sleeve in toggle-locking position;

Fig. 5 is a section on the line 5—5 of Fig. 2 and, Fig. 6 is a section on the line 6—6 of Fig. 2.

The embodiment of the invention chosen for illustration is shown in connection with such operating units as, for example, an electric heating furnace 11 for heating such workpieces as the shell forgings 12 illustrated in Fig. 1, and a quenching tank 13, or the like, for quenching or otherwise treating the heated forgings. A work supporting rail 14 is provided for the support and transfer between stations of the work holder which is suspended from a trolley 15 by an electric hoist 16 operated to raise or lower the work holder by conventional control cables 17 and 18, respectively.

A work holder constructed in accordance with

one embodiment of this invention is shown as suspended from each hoist in Fig. 1. At the left, over the furnace 11, the work holder is adjusted for short spacing between the work centers, while at the right the adjustment is for long spacing therebetween.

As illustrated, the invention comprises a work supporting member 21 having horizontal arms 22 formed by a tubular member 22 connected at opposite ends by threaded studs 23 to angular supporting brackets 24 clamped at the lower ends of tie-rods 25 which are secured at their upper ends to the opposite arms of a bracket 26 secured by the threaded shank of an I-bolt 27 to the upper end of a tubular stem 28 which forms with the horizontal arms 22 an inverted T-shaped supporting member. As illustrated, the I-bolt 27, bracket 26, and tubular stem 28 are also welded together.

20 A centrally located, relatively stationary work holder in the form of a work supporting hook 29 is secured to the lower side of the horizontal tubular arm 22 of the T-member, in any desired manner such, for example, as by welding. A 25 pair of relatively movable, work supporting members in the form of hooks 31 are movably supported on the horizontal arms 22, being secured in and suspended from work supporting carriages 32, each of which is suspended from a pair of 30 rollers 33 riding on the top of the tubular arms 22 on opposite sides of the stem 28. Each relatively movable hook 31 has a shank 34 extending through a slot 35 in the bottom of the associated arm 22 and into the interior thereof. A 35 helical tension spring 36 extends through the interior of the tubular member forming the arms and is connected at its opposite ends to the shanks 34 for normally drawing the carriages 32 and the work supporting hooks 31 inwardly to the inner ends of the slots 35, the inner ends of which determine the distances between the work holders when in position for short center spacing.

40 Means is provided for moving the work holders 31 outwardly along the tubular member to increase the center spacing thereof and to lock them in such position against the tension of the spring 36. As illustrated, this means includes 45 toggle links 37 connecting the work holder carriages 32 to a toggle actuating and locking sleeve 38 which is slidably mounted on the vertical hanger 28 of the T-shaped frame. Preferably a pair of links 37 connects each carriage with the sleeve, the links being connected to the extended ends of axles 39 on which one of the rollers 33 in each carriage is mounted and the oppo-

site ends of the toggle links are connected to ears 41 extending downwardly on opposite sides of the sleeve 38 at the lower end thereof. Washers or spacers 42 are provided to suitably space the parts. A handle 43 is provided on the toggle operating sleeve 38 for ease in operation.

As shown in Fig. 6, relative rotation of the horizontal tubular member 36 in the supporting angle brackets 24 is prevented by the key connection 44 therebetween.

In operation, assuming that the workpieces such, for example, as the shell forgings 12 are to be first subjected to the heating operation of the electric furnace 11 which calls for relatively short center spacing between the two 15 pieces, the sleeve 38 will be raised to the position shown at the left of Fig. 1 and in Fig. 2. This permits the coil spring 36 to draw the movable work supporting carriages 32 and hooks 31 inwardly to the inner ends of the slots 35, as shown 20 in solid lines in Fig. 2. The work holder and work supported thereon is lowered by the hoist 16 to subject the workpieces to the heating effect of the furnace. Thereafter, the work holder is raised by the hoist 16 and transferred along the rail 14 to the next operational unit such, for example, as the quenching bath 13 or other suitable apparatus which requires relatively longer spacing between the work centers. During movement of the work holder from one unit to the other, this increased spacing is easily and quickly accomplished by pulling the toggle-operating sleeve downwardly, through the medium of the handle 43, to the bottom of the vertical stem 28. This spreads the links 37 forcing the carriages 33 and work supports 31 apart to the position shown in dotted lines in Fig. 1. When the sleeve 38 is in the lowermost position, the ears to which the inner ends of the toggle links 37 are connected are positioned below a straight line connecting the opposite ends of the links, as shown in Figs. 2 and 4. This locks the toggle against the tension of the spring 36 and holds the work holders in the position of greater spacing necessary for treatment in the unit 13. In like manner, the work holders can be quickly returned to close spacing by lifting the sleeve 38 to break the toggle lock and permit the spring 36 to draw the work holders inwardly to the inner ends of the slots 35 and yieldingly hold them in such position.

Although a specific embodiment of this invention has been described in detail it will be apparent that the invention can be variously modified and adapted within the scope of the appended claims.

What is claimed is:

1. A work support for a plurality of workpieces comprising a work supporting member, relatively movable work holders mounted on said member, and toggle means for both relatively moving said holders on said member to vary the spacing therebetween and for locking said work holders in predetermined spaced position.

2. A work support for a plurality of workpieces comprising a work supporting member, a plurality of work holders slidably mounted on said member, means for yieldingly biasing said work holders towards each other to yieldingly hold them in relatively closely spaced positions, and means including toggle arms for shifting said holders apart to locate them in relatively spaced positions and for locking them therein.

3. A work support for a plurality of workpieces

comprising horizontally extending arms and a vertical stem, a plurality of work holders slidably mounted on said arms, means for yieldingly biasing said work holders towards each other, 5 toggle links connected to said members, and a toggle actuating sleeve slideable along said stem for operating said links to spread said holders apart and lock them in separated position, and to unlock said links to permit said spring to move said holders inwardly to predetermined position.

4. A work support for a plurality of workpieces comprising horizontally extending tubular arms, work supporting carriages slidably mounted on said arms, a spring extending through said tubular arms and connected to said carriages for drawing said carriages inwardly to predetermined position, means limiting the extent of inward movement of said carriages, and means for shifting said carriages outwardly against the tension of said spring to predetermined spaced positions and for locking said carriages in such spaced positions.

5. A work support for a plurality of workpieces comprising horizontally extending tubular arms and a vertical stem, work supporting carriages slidably mounted on said arms on opposite sides of said stem, a spring extending through said tubular arms and connected to said carriages for drawing said carriages inwardly to predetermined position, means limiting the extent of inward movement of said carriages, and means for shifting said carriages outwardly against the tension of said spring to predetermined spaced positions and for locking said carriages in such spaced positions, including a sleeve slideable on said stem and toggle links connecting said carriages and said sleeve.

6. A work support for a plurality of workpieces comprising horizontally extending tubular slotted arms and a vertical stem, work supporting carriages movable along said arms on opposite sides of said stem, a spring extending through said tubular arms and connected to said carriages for drawing said carriages inwardly to predetermined position, means on said carriages engaging the slots in said arms for limiting the extent of inward movement of said carriages, means for shifting said carriages outwardly against the tension of said spring to predetermined spaced positions and for locking said carriages in such spaced positions including a sleeve slideable on said stem and toggle links connecting said carriages and said sleeve, a hanger secured to the upper end of said stem and tie rods connecting said hanger to the outer ends of said tubular arms.

7. A work support for supporting a plurality of workpieces comprising a supporting frame, spaced workpiece holders mounted on said frame for relative movement toward and away from each other between minimum spaced and maximum spaced positions, resilient means urging said holders to one of said positions, and linkage mechanism interconnecting said holders, said linkage mechanism being arranged first to relatively move said holders to the other of said positions against the opposition of said resilient means and then to lock said holders against return movement by said resilient means.
